UNITED STATES PATENT OFFICE.

JOSEPH H. FUNK, OF NEW YORK, N. Y.

NECKBAND FOR SHIRTS.

1,097,856.

Specification of Letters Patent.

Patented May 26, 1914.

Application filed March 7, 1913. Serial No. 752,632.

To all whom it may concern:

Be it known that I, JOSEPH H. FUNK, a citizen of the United States, and a resident of the city of New York, borough of Manhattan, in the county and State of New York, have invented a new and Improved Neckband for Shirts, of which the following is a full, clear, and exact description.

This invention relates to improvements in neckbands, and has for an object to provide an improved structure for forming a neck or button guard which will be simple and economical in its make-up while thoroughly preventing the button from pressing against the neck.

A further object of the invention is the provision of a neckband cut so as to have an overlapping end portion for thickening or reinforcing the band at the end carrying the button so as to prevent the pressure of the button against the neck.

A still further object of the invention is to so form a neckband as to reduce the movements in the manufacture thereof to a minimum and at the same time provide button guards both at the front and back.

In carrying out the objects of the invention the band may be made of any desired number of plies, as for instance four, and a reinforcing pad may be connected to the band centrally thereof for acting as a reinforcing member or a rear button guard. One of the sections of the band may be made of an extra length, or rather with an extension which is adapted to be folded over simultaneously with the band and also simultaneously sewed in place for acting as a reinforcing guard or padding at the end of the band. In the construction and arrangement of the guards, the same are added or provided without requiring any additional movements in the folding or in the sewing of the various parts together so that the cost of production is not increased, while a resulting advantage is provided.

A practical embodiment of the invention is represented in the accompanying drawings forming a part of this specification in which similar characters of reference indicate corresponding parts in all the views.

Figure 1 is a perspective view of the neckband shown in position on a shirt having an open front; Fig. 2 is a view similar to Fig. 1, except that the band is shown on a shirt having an open back; Fig. 3 is a perspec-

tive view of a two-piece band arranged on a shirt open front and back; Fig. 4 is a plan view of one of the parts of the band; Fig. 5 is a plan view of a second part; Fig. 6 is an edge view of the various plies of the band arranged ready for stitching; Fig. 7 is a side view of the structure shown in Fig. 6; Fig. 8 is a side view of the band complete; Fig. 9 is a section through Fig. 8 on the line 9-9, the same being shown on an enlarged scale; Fig. 10 is a section through Fig. 8 on the line 10-10, the same being shown on an enlarged scale; Fig. 11 is a section through Fig. 10 on the line 11-11, the same being shown on an enlarged scale; Fig. 12 is a detail fragmentary perspective view showing the front part of the neckband and the guard or reinforcement arranged therein.

Referring to the accompanying drawings by numerals, 1 indicates an open front shirt provided with a band 2 formed as shown in Figs. 4 to 12, inclusive, but arranged for the open front shirt 1. This is also true of the bands 3 and 4 shown in Figs. 2 and 3, the only difference being between the band shown in Figs. 1, 2 and 3 are their adaptability to the various forms of shirt, the shirt shown in Fig. 3 being open front and back so that the band 4 will be formed in two pieces or parts.

In forming the detail parts of the band, the same may be made with any desired number of members and any desired number of plies. In Fig. 4 is disclosed part 5 which is adapted to be folded upon line 6. Extending from one end of part 5 is a tab 7 adapted to be folded at the same time as part 5 on the line 6, and then folded on line 8 so as to assume the position shown in Fig. 6. Part 9 shown in Fig. 5 is adapted to be creased on line 10 and to be arranged adjacent part 5, as shown in Figs. 6 and 7, after which a line of stitching 11 is placed in position, which will connect these two parts along one edge. An extra tab 12 is placed with one edge adjacent the edge of the parts 6 and 9 and connected thereto by a line of stitching 11, as shown in Fig. 10. This extra tab 12 is designed to act as a guard at the rear of the band for reinforcing the band at that point and preventing a button arranged in the button-hole 13 from causing a pressure on the neck. After the line of stitching 11 has been placed in posi-

tion the band is reversed or turned to the position shown in Figs. 9 to 12 inclusive and then a second line of stitching 14 is placed in position as shown in Figs. 8 to 12 inclusive for forming a proper upper edge to the band. When reversing the parts 4 and 5 so that they will occupy the position shown, as for instance in Fig. 12, the extension or guard 7 will be turned under to the position shown in Fig. 12 and when the line of stitching 15 is placed in position the same starts at point 16 and skips the outer ply or two plies of part 6 but passes through the end of part 5, the shirt 1, and the guard 7. When the needle in the machine reaches the point 17 it is caused to move over so as to include parts 5 and 9 until it reaches point 18 (Fig. 8) where part 6 is raised in order that the needle will skip the same until it reaches point 19, whereby an opening is provided opposite the button hole 13. This will allow the button to be easily placed in position or removed. From point 19 it passes in the usual manner to point 20. When it is desired to finish up the neckbands without connecting the same with a shirt, an extra line of stitching 21 is provided in the usual manner for holding the various parts properly together. By arranging the guard or tab 7 as a part of part 6, the same may be folded in position and sewed down without any extra movements upon the part of the operator. This is also true in regard to the tab 12 as the same is sewed in position by the same line of stitching that is used for sewing the remaining part of the neckband together. In this way a simple strong and economical band is provided which presents the additional advantage of a reinforced or guarded buttonhole both in the back of the band and in the end thereof.

Having thus described my invention I

claim as new and desire to secure by Letters Patent:—

1. A neckband of the class described comprising a body formed of a plurality of parts, one of said parts being formed with an extension at one end, said extension being of the same width as the adjacent portion of said last mentioned part, said last mentioned part being adapted to be folded along a line extending through the center thereof longitudinally and also extending through said extension, said extension being adapted to be folded at the same time as said last mentioned part, said extension also being adapted to be folded over against said last mentioned part, and lines of stitching for connecting said parts together and said extension to one end of one of said parts, said extension acting as a button shield.

2. In a neckband of the class described, a body formed of a pair of members adapted to be folded on a line extending longitudinally thereof, one of said members being formed with an extension projecting from one end designed to be folded simultaneously with the part with which it is connected, said extension being adapted to be folded over against said last mentioned member after said last mentioned member has been folded, a line of stitching extending through both of said members and said extension along one edge, and a line of stitching extending through all of said members except at the point opposite said extension and the center buttonhole.

In testimony whereof I have signed my name to this specification in the presence of two subscribing witnesses.

JOSEPH H. FUNK.
